UNITED STATES PATENT OFFICE

ROCKEL ALEXANDER FRITSCH, OF CHICAGO, ILLINOIS, ASSIGNOR TO JOHN LAWRIE,
OF CHICAGO, ILLINOIS

FOUNTAIN PEN

Application filed October 17, 1927. Serial No. 226,701.

This invention relates to self-filling fountain pens of the type that are filled through the writing end, and aims to provide a pen that may be filled by a single complete stroke of the piston, and characterized by large ink capacity in proportion to its size, by simplicity of construction, and by absence of openings other than at the writing end. Other objects and advantages will be apparent from the following specification and accompanying drawings which illustrate embodiments of my invention.

In the drawings, throughout which the same reference characters refer to like parts, Fig. 1 is a longitudinal central section of a preferred form of my pen, showing the relative positions of piston and barrel at the completion of the filling stroke;

Fig. 2 is a view similar to Fig. 1, showing a modified form;

Figs. 3, 4, 5 and 6 are cross-sections on lines 3-3, 4-4, 5-5, and 6-6, respectively, of Fig. 1, Figs. 3 and 6 being taken in the direction of the arrows; and

Fig. 7 is a cross-section on line 7-7 of Fig. 2.

Referring particularly to Fig. 1, the preferred form of my fountain pen comprises a barrel 1 of uniform interior cross-section, free from openings or movable parts except at the lower or writing end. A tubular bushing or end plug 2, screwed or otherwise secured in the lower end of the barrel, forms a continuation thereof and closes it except for a relatively small central axial aperture 3, of circular cross-section, outwardly flared at the inner end and which serves as a guide for the axial piston stem 4, extending through it. The stem 4 closes the aperture 3 except in its inmost position, and is longitudinally perforated, as at 5 and 6, the perforations 5 being closed at each end but open at the side near each end, while the perforation 6 is open only at the ends. The barrel and its associated closing elements constitute an ink reservoir 7. In the outer end of the bushing 2 is a frusto-conical recess or socket 8, narrowing upward from the lower end, coaxial with the aperture 3 with which it communicates.

The filling and writing mechanism of my improved pen comprises a reciprocable closing and point-carrying member 9 (hereinafter called the point-carrier as a convenient designation) external to the lower end of the barrel, and normally seated in the socket 8. The point-carrier is connected by means of the axial stem 4 to a piston 10 which, when all the elements are in writing position, is in the upper end of the barrel 1.

The piston 10 is preferably made in the form of a flat cylinder, screwed or otherwise securely fastened onto the stem 4, the upper end of the stem being flush with the upper side of the piston. The piston is made self-sealing by circumferential grooves 11, or other suitable means.

The barrel 1 may be externally threaded near its point, as at 22, for the attachment of a cap 23. A shoulder 24 within the cap abuts against a ring-shaped lug 13 on the outside of the point-carrier 9, and this lug may be provided with annular grooves 24, forming a seal against ink leakage. Similar annular grooves 26 may be provided on the front of the bushing 2 to restrain side creeping of ink thereupon.

The point-carrier 9 in the embodiment shown is made in two parts, and includes a sleeve 12, externally divided about the middle by the circumferential ring-shaped lug 13 (which preferably is of the same size as the face of the bushing 2), the portion outside of or below the lug 13 being cylindrical, and that above or inside of the lug being tapered to correspond with and seat firmly in the conical recess 8. Within the sleeve 12 a feed piece 14 is held, preferably by a friction fit, sufficient clearance (as at 15) being left between the inner face of the feed piece and the transverse face of the recess 8 so that ink may flow across the inner end of the feed piece. The outer end of this feed piece 14 projects beyond the sleeve 12, forming a support for a pen point 16 whose inner end is securely held between the feed piece and the sleeve. Said projecting outer end is extended at one side in the usual manner, forming a pen point support. A capillary ink duct 17 extending from the inner end

of the feed piece 14, beneath the pen point to just short of the outer end of the supporting portion, allows feed of ink to the point when writing. Another ink passage 18, inclined inward at an acute angle to the duct 17, 5 leads from about the middle of said duct to the interior of the feed piece 14 connecting with the opening 28 in the passage 5 in the stem 4. A passage is formed longitudinally 10 through the feed piece 14 by two holes of different sizes, 19, 20, which align end to end but are not necessarily coaxial. The outer end of the central stem 4 is screwed or otherwise suitably secured in the inner of these, 19, 15 which is the larger, in such manner as to bring the longitudinal perforation 6 into registry with the smaller hole 20, providing a vent for escape of air from the portion of the reservoir 7 above the piston 10.

20 The stem 4 is sized to make a sliding but ink-tight fit in the hole 3, but is cut away at its outer end on one side, as at 21, Figs. 1 and 4, to permit flow of ink from the reservoir into the space 15 above the feed piece 14, 25 and so to the duct 17, when in its normal innermost position. The side openings 27 and 28 near the inner and outer ends of the longitudinal perforation 5, (Figs. 1, 3 and 6) permit flow of ink, during filling, inwardly 30 through the successive passages 17, 18 and 5 into the reservoir 7.

The modified form of my pen illustrated in Fig. 2, comprises substantially the same elements and arrangement as are shown in Fig. 35 1, the principles of operation being the same. For this reason only such parts as differ from the corresponding parts of the form shown in Fig. 1 will be described herein.

40 The bushing 31, the tapered recess 32, the tapered sleeve 33, and the feed piece 34 are all longer than the similar elements in Fig. 1. The stem is composed of two concentric tubes, of which the inner 35, is considerably 45 longer than the outer, 36. This inner tube is screwed or otherwise fastened through the piston 37 at its inner end, and into the feed piece 34 at its outer end, and is open only at its ends. The outer tube 36 is sufficiently 50 larger than the inner tube to allow an ink passage 38 between the two. One end of this outer tube is fastened into but not through the piston 37, so that the passage 38 is closed at the inner end by the piston. A side opening 39 adjacent to the piston allows ink to 55 enter the reservoir 40.

An axial passage extends through the feed piece 34. The outer end of the outer tube 36 screws or fastens otherwise into the inner 60 end of this passage, about three-fourths of the adjacent length of the passage being substantially the same diameter as the inside of the outer tube, as at 41, Fig. 2. The inner tube 35 is fastened, by screw threads or otherwise, into the feed piece at the end of the en-

larged portion of the passage 41, the axial passage being continued through to the outer end of the feed piece by a bore 42 of the same diameter as the inside diameter of the inner tube.

70 The external circumference of the outer tube is reduced, at its end, as at 43, where it passes through the axial aperture 44 in the bushing 31, to allow feed of ink when writing, but this aperture is of a size to make a close sliding fit with the main length of the tube as soon as the filling stroke begins.

75 It will be understood that the inner tube 35 serves as an air vent when filling and that the passage 38 similarly serves as an ink passage into the reservoir in the same manner as the passages 6 and 5, respectively, in the form of pen illustrated in Fig. 1.

80 The clearance space 45, ink duct 46, and inclined passage 47, correspond in function 85 to the clearance space 15, ink duct 17 and inclined passage 18, respectively, of the device illustrated in Fig. 1.

85 For facility in grasping the pen, the periphery of the annular lug 48 may be knurled, as at 49.

90 In all embodiments of my invention the various elements may be either integral or assembled of separate pieces, as preferred, and the assembly may be made in any suitable and convenient manner, as by screw 95 threaded engagement, friction fit, or the like.

95 It will be understood that mutually consistent elements from either form of my pen herein shown and described may be combined otherwise than as shown without departing from the spirit of my invention. In particular, the bushing, tapered recess, and sleeve in either form may be either long or short, as preferred, provided always that the 100 tapered surfaces be of sufficient area and at a suitable angle to grip the sleeve firmly in the bushing, so that the point-carrier will be rigid with respect to the barrel while writing, and to make an ink-tight joint.

105 It will be noted that this rigidity is furthered by the provision of a relatively large tapered recess and a relatively large tapered surface preferably made integral with the point carrier as shown, and having a manipulating flange or surface of a relatively large diameter whereby the tapered surfaces may be firmly forced together for a rigid and ink-tight fit, and whereby any danger of breaking the more delicate parts of the pen when 110 attempting to pull out the point carrier is avoided. Thus, this construction permits the use of a relatively small piston rod with consequent increase in the reservoir capacity, as the rod is at no time under any great strain 115 (it being provided with a freely sliding, though substantially ink-tight fit with its bore, as noted above) and as a firm grip may be obtained on the flange to slightly turn the tapered surfaces on one another to firmly 120

125 130

seat, or readily separate, the same, without the exertion of so much longitudinal or transverse force as would tend to break or injure the pen.

- 5 The filling of my present form of pen is accomplished by a single complete stroke of the piston relative to the barrel, comprising one movement of the piston from inner to outer end of the barrel and back to the inner 70 end. This filling stroke is conveniently made by holding the barrel in one hand and the circular lug in the other, the pen point being in the air, pulling the barrel up until the inner face of the bushing is stopped by the piston, 75 then immersing the pen point in ink and pushing the elements together again until the sleeve seats securely in the tapered recess. It will be observed that the beginning of the out stroke brings the full diameter of 80 20 the stem into the central aperture through the bushing, thus cutting off exit of ink through the writing flow channel. During the outer half of the filling stroke escape of air or ink or both in the reservoir is, however, 85 permitted by the ink intake passages. Ingress of air through the air vent passages prevents the formation of a vacuum in the upper part of the barrel. Although the lower part of the point-carrier may be submerged 90 25 in ink during outward portion of the filling stroke, so that ink may be sucked up into the space above the piston, no damage will result, because this ink will merely be forced out through the same channel during 95 30 the return portion of the stroke, which fills the reservoir, and as this channel terminates below any point on the pen grasped either in writing or filling the same, there is no danger of soiling the fingers with any 100 35 ink which may issue therefrom due to such intake, or to leakage past the piston which might develop after long use. Thus piston packing may even be entirely dispensed with in favor of the simple sealing grooves 11, as 105 40 noted above, and repair work is minimized. 45
- On the return half of the stroke the barrel is pushed downward, creating a vacuum below the piston, drawing ink into the reservoir through the inclined aperture, the appropriate channel of the central stem, and the opening just below the piston. The ink inflow channel of course communicates freely with the ink supply by way of the normal pen point orifice, and the length and capillarity of the point carrier ink feeding channel, and the fact that it affords but a restricted and indirect communication between the ink inflow passage and the atmosphere, effectively prevents any sucking in of air during the filling operation, so that the reservoir may be substantially entirely filled by a single complete stroke of the piston, inasmuch as the central tube cuts off all communication between the reservoir and the exterior save through the filling passage during the

filling operation. This communication is cut off until completion of the filling stroke when the contracted portion of the central tube comes within the opening of the bushing, permitting the flow of a quantity of ink sufficient for writing. 70

While I have shown and described my invention for use with the usual type of pen point, it will be understood that any other writing element, such as a stylus, not inherently incapable of use in combination with the other features of the invention, may be employed. 75

From the foregoing it will be seen that I have invented a fountain pen of simple construction, free from valves, springs or sacks, and having no openings in the upper part or the sides of the barrel, thus avoiding the liability of leakage. By reason of simplicity of construction my pen is capable of being 80 cheaply manufactured, and is durable and not easily put out of order. By virtue of the tapered fit of the closing member in the bushing, no screw threads or lugs are required to hold the closing member in place and no 85 twisting motions are necessary before or after the filling stroke as would be required with screw threads, bayonet joints, or lugs. It will be observed that the flow of ink during the filling stroke of my pen is through 90 a channel having no sharp change of direction until the outlet at the inner end of the central tube is reached, so that inflow of ink is not retarded. This gives an efficiency of 95 action resulting in complete filling of the 100 reservoir at a single stroke.

It is to be understood that the foregoing description of my invention is to be taken in an illustrative but not in a limiting sense, the scope of the invention being as set forth 105 in the appended claims.

What I claim is:

1. A fountain pen comprising in combination, a barrel and a bushing which constitute a rigid cylindrical reservoir having an opening only in the writing end, a hollow stem adapted to slide in said opening, a piston upon one end of said stem adapted to be reciprocated thereby in said reservoir, a point-carrier external to said reservoir upon the opposite end of said stem, said point-carrier being adapted to seat in said bushing, and ink and air channels through said point-carrier and through said stem into said reservoir. 110 115

2. In a self-filling fountain pen, in combination, a rigid reservoir open only at the point end, a bushing for said end, a point-carrier normally seated in said bushing, a close-fitting piston normally positioned in the 120 inner end of said reservoir, a hollow stem connecting said point-carrier with said piston, a feed channel through said point-carrier, a filling channel through said point-carrier and through said stem, and an air vent 125 130

through said point-carrier, through said stem, and through said piston.

3. In a self-filling fountain pen, in combination, a rigid barrel, a bushing forming therewith an ink reservoir, a tapered recess in the outer end of said bushing, a point-carrier adapted to fit firmly within said recess, a piston reciprocable within said barrel, and a rigid connection between said piston and said point-carrier.

4. In a self-filling fountain pen, in combination, a combined barrel and reservoir solidly closed except at the point end, a piston adapted to travel the full length of said reservoir, and filling means associated with said piston whereby to practically entirely fill said reservoir by a single movement of said piston from the lower to the upper end thereof.

5. A fountain pen comprising, in combination, a barrel solidly closed at one end and having at its other end an end member provided with a relatively small axial aperture terminating externally in a relatively large inwardly tapered recess, a piston within said barrel, a hollow stem attached thereto and extending through said aperture and of such size as to be freely slidable therethrough but with a substantially ink tight fit, a point carrier attached to said stem outside said barrel and provided with a surface to complementarily seat in said recess and an enlarged manipulating flange, a channel in said point carrier communicating with said hollow stem, an opening in said hollow stem for establishing communication between said stem and the interior of said barrel, and means for feeding ink from said barrel to said point carrier, substantially as and for the purposes described.

6. A fountain pen comprising, in combination, a barrel solidly closed at one end and having at its outer end an end member provided with a relatively small axial aperture terminating externally in a relatively large inwardly tapered recess, a piston within said barrel, a hollow stem attached thereto and extending through said aperture and of such size as to be freely slidable therethrough but with a substantially ink tight fit, a point carrier attached to said stem outside said barrel and provided with a surface to complementarily seat in said recess and an enlarged manipulating flange, a channel in said point carrier communicating with said hollow stem, an opening in said hollow stem for establishing communication between said stem and the interior of said barrel, and means comprising a channel opened past said barrel end member and communicating with said point carrier when said tapered surfaces are seated for feeding ink from said barrel to said point carrier, substantially as and for the purposes described.

7. A fountain pen comprising, in combina-

tion, a barrel solidly closed at one end and having at its other end an end member provided with a relatively small axial aperture terminating externally in a relatively large inwardly tapered recess, a piston within said barrel, a hollow stem attached thereto and extending through said aperture and of such size as to be freely slidable therethrough but with a substantially ink tight fit, a point carrier attached to said stem outside said barrel and provided with a surface to complementarily seat in said recess and an enlarged manipulating flange, a channel in said point carrier communicating with said hollow stem, an opening in said hollow stem for establishing communication between said stem and the interior of said barrel, and means comprising a reduced portion of said stem adapted to extend through said aperture when said tapered surfaces are seated and a communication therefrom to said point carrier for feeding ink from said barrel to said point carrier, substantially as and for the purposes described.

8. A fountain pen comprising, in combination, a barrel solidly closed at one end and having at its other end an end member provided with a relatively small axial aperture terminating externally in a relatively large inwardly tapered recess, a piston within said barrel, a hollow stem attached thereto and extending through said aperture and of such size as to be freely slidable therethrough but with a substantially ink tight fit, a point carrier attached to said stem outside said barrel and provided with a surface to complementarily seat in said recess and an enlarged manipulating flange, a channel in said point carrier communicating with said hollow stem, an opening in said hollow stem for establishing communication between said stem and the interior of said barrel, and means comprising a reduced portion of said stem adapted to extend through said aperture to the bottom of said recess when said tapered surfaces are seated and a communication from the bottom of said recess to said point carrier for feeding ink from said barrel to said point carrier, substantially as and for the purposes described.

9. In a fountain pen, in combination, a rigid barrel, a bushing forming therewith an ink reservoir and having a relatively small aperture, a relatively large inwardly tapered recess in the outer end of said bushing and coaxial with said aperture, a point carrier adapted to fit firmly within said recess, a piston reciprocable within said barrel, a rigid stem connecting said piston and said point carrier and of such size as to be freely slidable through said aperture but to have a substantially ink-tight fit therewith, and means for feeding ink from said reservoir to said point carrier.

10. A fountain pen comprising in combi-

- nation, a barrel and a bushing which constitute a rigid cylindrical reservoir having an opening only in the writing end, a hollow stem adapted to slide in said opening without binding, a piston upon one end of said stem adapted to be reciprocated thereby in said reservoir, a point-carrier external to said reservoir upon the opposite end of said stem, said bushing being provided with an inwardly inclined binding surface, said point-carrier being formed with a portion complementary to said binding surface and arranged for engagement therewith, and ink and air channels through said point-carrier and through said stem into said reservoir.
- 5 10 15 20 25 30 35 40 45 50 55
11. In a self-filling fountain pen, a rigid barrel closed at one end, a bushing at the other end forming with said barrel an ink reservoir and having an aperture, an inwardly inclined binding surface at the outer end of said bushing, a point carrier formed to engage with said binding surface with a closing fit, a piston reciprocable within said reservoir and a rigid filling tube between said piston and said point carrier easily slidable through said aperture.
12. As an element in a self filling fountain pen of the type in which there is a piston filler adapted to be actuated from the writing end of the pen barrel to fill the pen by a single stroke from one end of the barrel to the other, venting means for the space on the side of the piston opposite to that part of the barrel comprising the ink reservoir, said venting means opening to the exterior of the pen at a point adjacent the writing end thereof and beyond any part of the pen normally grasped in writing with, or in filling the same.
13. As a sub-combination in a self-filling fountain pen of the type in which there is a piston filler including an element relatively movable with respect to the barrel assembly to be manually actuated in the filling operation and a finger grip element formed on the part to be manually actuated adjacent a point of possible leakage between the relatively movable element and the barrel assembly, a portion on said barrel assembly in opposition to part of said relatively movable element, and a series of ridges formed on one of said opposed parts to aid in preventing any leakage which might occur at said point of possible leakage from reaching the surface of said finger grip element.
- 14 19 24 29 34 39 44 49 54
- 56 In testimony whereof, I have signed my name to this specification.

ROCKEL ALEXANDER FRITSCH.
